UNITED STATES PATENT OFFICE.

ADOLPH PETZOLD, OF PHILADELPHIA, PENNSYLVANIA, ASSIGNOR TO JOHN H. BROMLEY AND EDWARD BROMLEY, COPARTNERS TRADING AS JOHN BROMLEY & SONS, OF PHILADELPHIA, PENNSYLVANIA.

DESIGN FOR A RUG.

43,432.

Specification for Design.

Patented Jan. 7, 1913.

Application filed November 15, 1912. Serial No. 731,603. Term of patent 3½ years.

To all whom it may concern:

Be it known that I, ADOLPH PETZOLD, a citizen of the United States, residing in the city of Philadelphia, State of Pennsylvania, have invented a certain new, original, and ornamental Design for Rugs, of which the following is a specification, reference being had to the accompanying drawing, forming part thereof.

The figure is a plan view of an Axminster rug showing my new design.

I claim:

The ornamental design for a rug, as shown.

ADOLPH PETZOLD.

Witnesses:

A. M. BIDDLE,
R. A. DUNLAP.
